UNITED STATES PATENT OFFICE

2,056,264

TUYÈRE

Gordon Fox, Chicago, Ill., assignor to Freyn Engineering Company, Chicago, Ill., a corporation of Maine

Application March 30, 1935, Serial No. 13,845

7 Claims. (Cl. 122—6.6)

The present invention relates to tuyères.

Patent No. 1,969,693, granted August 7, 1934, to Gordon Fox and Arthur J. Whitcomb, discloses a tuyère to be used in a blast furnace for directing hot air into the furnace. Said patent discloses means for directing cooling medium at relatively high velocity through the nose region of the tuyère and along the inner and outer cone walls of the tuyère adjacent to the nose of the tuyère. Said patent also discloses a construction in which the material of the tuyère is so disposed as to efficiently conduct heat units applied to the tuyère, particularly at the nose region thereof, to the rapidly flowing cooling water. The heat units referred to are derived from several sources, including the hot blast directed through the tuyère, radiation and convection from within the furnace, and from splashes of molten metal or slag coming in contact with the tuyère.

Tuyères are commonly made of copper, which melts at about 1800 to 1900 degrees F. Tuyères are exposed to furnace temperatures in the neighborhood of 3000 degrees F. Molten material such as hot metal at perhaps 2500 to 2800 degrees F. sometimes pours upon them or splashes against them. This contact with hot metal is probably the principal cause of tuyère failure.

Tuyères are ordinarily cooled by circulating water through them. Molten iron contacting with the copper of an ordinary tuyère can impart heat to the copper much faster than the cooling water can take it away from adjacent copper. The present invention contemplates a construction in which the vast difference between the heat transmissiveness from the iron to the copper on the one hand and the heat transmissiveness from the copper to the water on the other hand will be compensated for to a considerable extent.

More particularly, the present invention has for one of its objects the provision of an improved tuyère in which the metal thereof is so disposed as to provide improved efficacy per unit weight of copper in protecting the tuyère against splashes of molten metal and the like.

A further object is to provide an improved tuyère in which the metal thereof is so disposed as to provide for efficient high velocity flow of water through the nose region thereof and at the same time to provide improved efficacy per unit weight of copper in transferring heat units from the outer wall of the tuyère to said water under the emergency conditions referred to.

A further object is to provide an improved tuyère in which, in normal operation, heat received in the nose region of the tuyère is encour-

aged to flow through the walls of the tuyère to regions adjacent to the base of the tuyère which are normally cooler.

A further object is to provide a tuyère which, in normal operation, will have a more uniform 5 temperature throughout than has heretofore been common.

A further object is to provide a tuyère which will not succumb easily to transient contacts with 10 molten metal.

A further object is to provide an improved tuyère well adapted to meet the needs of commercial service.

Further objects will appear as the description 15 proceeds.

In perfecting the present invention applicants have utilized two factors, as follows:

(a) The molten metal referred to usually contacts with only a small area of the tuyère copper. The cooling water contacts the entire water 20 chamber. The water has a big advantage as to area of contact surface. By utilizing a high velocity of water flow over substantial portions of said relatively large area of water contact surface, a portion of the tremendous difference in heat 25 transmissiveness between the molten iron and the copper on the one hand and the copper and the water on the other hand is compensated for.

(b) Applicant furthermore has utilized the ability of the copper to absorb and store heat, and 30 has so chosen the distribution of the metal of the tuyère as to make effective use of this absorbing and storing ability. The copper of the tuyère can absorb heat from a splash of molten metal during a short interval of time (by a rise 35 in copper temperature), and can subsequently, over a greater period of time, dispel that heat to the cooling water. By reason of improved disposition of the copper in the outer cone wall of the tuyère, that is—in close thermal conductive 40 relation to the probable area of hot metal contact, the above mentioned difference between the heat transmissiveness from the molten metal to the copper on the one hand and from the copper to the cooling water on the other hand can be further compensated for.

The present invention makes use of the two factors above described as follows:

1. The areas likely to be subjected to hot metal attack will have heavy walls both in order to 50 spread the heat from the concentrated hot metal attack to more water surface and in order to enlist the maximum adjacent mass of copper as a storage means.

2. The heavy walls referred to will in normal 55

operation be as cool as possible in order that the copper therein may have a maximum temporary heat absorptive capacity.

3. The heavy walls in the most vulnerable regions will enable a certain amount of outer surface melting of the copper to occur without leading to leakage and failure.

The present invention, therefore, contemplates a construction in which cooling water is directed at high velocity through the nose region of the tuyère in close contact with the inner surfaces of the nose wall, and in which a heavy nose and heavy side walls are provided, the outer side wall being particularly heavy, in the nose region of the tuyère, with reference to the inner side wall. In other words, the present invention contemplates a construction having a heavy nose and heavy inner and outer side walls in the nose region of the tuyère, the outer side wall in said nose region being appreciably heavier than the inner side wall. This construction is embodied in a tuyère which provides extended water-contacting surfaces in the nose region. High velocity flow is provided past the inner surface of the heavy outer side wall. These provisions insure a maximum rate of heat dissipation from increased areas directly to the water during periods of hot metal attack, and maintain the copper in the nose region very cool during normal operation, so that said substantial mass of copper has maximum temporary heat absorptive ability.

Referring to the drawings—

Figure 1 is a view in elevation illustrating an embodiment of the present invention;

Figure 2 is a bottom plan view of the structure shown in Figure 1;

Figure 3 is a sectional view taken along the plane indicated by the arrows 3-3 of Figure 1;

40 Figure 4 is a fragmentary sectional view taken along the plane indicated by the arrows 4-4 of Figure 2;

Figure 5 is a fragmentary sectional view taken along the plane indicated by the arrows 5-5 of Figure 2 but showing a modification;

Figure 6 is a view similar to Figure 5 but showing an outer side wall of the same general contour as that shown in Figure 4 and having an inner side wall differing in some respects from the inner side wall shown in Figure 4; and

Figure 7 shows another modification.

Referring first to Figures 1, 2 and 3, a tuyère is illustrated having the usual cone shape, said tuyère including the nose wall 10, the rear wall 11, the inner side wall 12, and the outer side wall 13, which walls provide an annular jacket for cooling medium, which jacket is indicated as a whole by the numeral 14. The walls referred to enclose the throat 15, through which the hot blast is directed into the blast furnace. The numerals 16—16 indicate openings in the rear wall 11, one of which would be connected to a water inlet pipe and the other of which would be connected to a water outlet pipe. Said two openings are preferably, though not necessarily, disposed adjacent to each other, and in the preferred construction will be separated by a radial partition 17 extending from the rear wall 11 to the nose wall 10 of the tuyère. By reason of this preferred construction, the water entering through one of the openings 16 is caused to pass through a series course to the outlet opening 16.

As hereinabove mentioned, the present invention contemplates a high velocity of water flow through the nose region of the tuyère, where

the tuyère is subjected to the severest attacks. It will be understood, of course, that in certain of its aspects the present invention is not limited to a particularly high velocity of flow of the cooling water, though, to utilize the advantages of the present invention to the maximum, a high velocity of cooling medium through the nose region is preferred. The means for providing the high velocity referred to may be chosen as desired. At present it is preferred to use the 10 construction disclosed in Patent No. 1,969,693.

Referring briefly to the means referred to for producing high velocity in the nose region of the tuyère, the accompanying drawings show barriers 18-18 extending longitudinally from the rear wall 11 toward the nose end of the tuyère. Said barriers 18-18 are radially disposed and are integrally united with the outer side wall 13 and the inner side wall 12. Said barriers are preferably uniformly spaced with respect to each other. 20 The grouping is preferably symmetrically spaced with reference to the partition 17. Extending from the nose wall 10 toward the rear end of the tuyère are a plurality of radially disposed barriers 19-19, which are preferably uniformly 25 spaced with respect to one another and to the partition 17. Said barriers 19-19 extend to the region of the extremities of the barriers 18-18, whereby water passing said barriers is forced to take a circuitous path, as illustrated by 30 means of the arrows in Figure 1. There is preferably, but not necessarily, an overlapping relationship between the furthermost extremities of the barriers 18-18 and the rearmost extremities of the barriers 19-19. The barriers 19-19 35 are connected to the nose wall 10 by rounded corners, and tapered from the nose wall in such a manner as to permit the ready flow of heat thereto from said nose wall 10. The barriers 19-19 will preferably not extend into the rear 40 portion of the tuyère but should stop in the nose region thereof.

As indicated hereinabove, the present invention contemplates a construction in which the outer side wall in the nose region of the tuyère 45 is decidedly heavier or thicker than is the inner side wall in the same region. The junctures between the nose wall 10 and the inner and outer side walls and between said walls and the barriers above referred to should be rounded, particularly in the nose region of the tuyère, whereby to avoid any danger of formation of pockets and whereby to provide for the complete scouring action between the cooling water and the surfaces with which they contact. In order to 50 define the regions of the tuyère to which the present invention is applicable, the complete length of the water jacket 14, that is—the maximum overall length of said water jacket, has been indicated by the letter X. The plane transverse 55 to the axis of the tuyère which indicates the innermost extremity of the water jacket has been indicated in Figures 4 to 7 inclusive by the reference characters A—A. The corresponding plane, indicating the outermost limit of said water 60 jacket, that is—the limit defined by the rear wall, has been indicated by the reference characters C—C. According to a certain preferred design of the invention, a distance approximately equal to $\frac{1}{5}$ X may be utilized in the rounded corners or fillets providing the juncture between the inner and outer side walls and the nose wall of 65 the tuyère. The plane transverse to the axis of the tuyère marking the distance $\frac{1}{5}$ X from the plane A—A has been indicated by the reference 70 75 70 characters $\frac{1}{5}$ X.

characters B—B. The length of the inner and outer side walls with which the present invention is concerned extends from the inner extremity of the water chamber 14 rearwardly from the nose wall 10 a distance approximately equal to $\frac{1}{3} X$. The plane spaced from the inner extremity of the water chamber a distance equal to $\frac{1}{3} X$ has been indicated by the reference characters D—D. According to the present invention, the average thickness of the outer side wall 13 in the region between the plane B—B and the plane D—D is at least $1\frac{1}{2}$ times the average thickness of the inner side wall 12 in the same region. A construction which falls within the scope of the present invention and which will accomplish a part of the advantages of the structure just described is one in which the thickness of the outer side wall 13 at any point in the region between the plane B—B and the plane D—D is at least $1\frac{1}{2}$ times the thickness of the inner side wall 12 measured in the same plane parallel to planes B—B and D—D. The minimum thickness of the nose of the tuyère is at least equal to the average thickness of the outer side wall 13 between the planes B—B and D—D.

In Figure 4 the thickness of the outer side wall 13 and the thickness of the inner side wall 12 are each substantially uniform from the plane B—B to the plane C—C.

According to the structure shown in Figure 5, both the outer side wall 13 and the inner side wall 12 taper in thickness rearwardly from the plane B—B to the plane D—D.

According to the construction shown in Figure 6, the outer side wall 13 is substantially uniform in thickness from the plane A—A to the plane C—C, whereas the inner side wall 12 tapers from the plane B—B to and beyond the plane D—D.

According to the structure shown in Figure 7, the outer side wall 13 tapers from the plane B—B to the plane C—C, whereas the inner side wall 12 is substantially uniform from the plane B—B to the plane C—C.

These and other modifications may be employed.

In recapitulation, it may be pointed out that the inner side wall 12 of a tuyère receives much heat from the air blast, hence this wall is quite hot in normal operation. The nose 10 of the tuyère receives much heat by radiation from the furnace. This tends to be the hottest part of the tuyère. The outer side wall receives radiant heat from the furnace in the region adjacent to the nose of the tuyère, but it receives little heat from the furnace in its mid region and in the region adjacent to the back wall. By means of the heavy outer side wall 13, a substantial part of the heat absorbed in the nose region of the tuyère is conducted axially down this outer side wall toward the base of the tuyère and is transferred from the outer side wall 13 to the water from the inner surfaces of side wall 13 in regions where these inner surfaces would otherwise transfer little heat to the water. This results in a tuyère which is cooler in normal operation.

Though certain preferred embodiments of the present invention have been described in detail, many modifications will occur to those skilled in the art. It is intended to cover all such modifications that fall within the scope of the appended claims.

What is claimed is—

1. In a tuyère, in combination, a nose wall, a rear wall, an inner side wall and an outer side wall forming an annular chamber for cooling water,

and means within said tuyère for setting up a high velocity of cooling water in the nose portion of said tuyère relative to the flow adjacent to the base of said chamber, the average thickness of said outer side wall in the nose region of said tuyère being at least one and one-half times the average thickness of said inner side wall in said nose region, said nose wall having a minimum thickness at least equal to said average thickness of said outer side wall in the nose region of said tuyère.

2. In a tuyère, in combination, a nose wall, a rear wall, an inner side wall and an outer side wall forming an annular chamber for cooling water, said outer side wall having an average thickness at least one and one-half times as great as the average thickness of said inner side wall in a region bounded by two planes disposed transversely of the tuyère, one spaced from the innermost end of said chamber a distance equal to approximately one-tenth of the overall length of said chamber, the other of said planes being spaced from the inner extremity of said chamber a distance equal to approximately one-third of the overall length of said chamber, said nose wall having a minimum thickness at least equal to said average thickness of said outer side wall in said region, and means for setting up a high velocity of water flow in the forward third of said chamber relative to the flow adjacent to the base of said chamber.

3. In a tuyère, in combination, a nose wall, a rear wall, an inner side wall and an outer side wall forming an annular chamber for cooling water, said outer side wall having an average thickness at least one and one-half times as great as the average thickness of said inner side wall in a region bounded by two planes disposed transversely of the tuyère, one spaced from the innermost end of said chamber a distance equal to approximately one-tenth of the overall length of said chamber, the other of said planes being spaced from the inner extremity of said chamber a distance equal to approximately one-third of the overall length of said chamber, the total thickness of said walls in the region between said planes tapering in thickness from said first-mentioned plane toward said second mentioned plane, said nose wall having a minimum thickness at least equal to said average thickness of said outer side wall in said region, and means for setting up a high velocity of water flow in the forward third of said chamber relative to the flow adjacent to the base of said chamber.

4. In a tuyère, in combination, a nose wall, a rear wall, an inner side wall and an outer side wall forming an annular chamber for cooling medium, barriers extending from said nose wall within said chamber toward said rear wall, and means for causing cooling water to flow back and forth along said barriers longitudinally of said tuyère while traveling circumferentially of said tuyère, said outer side wall having an average thickness at least one and one-half times as great as the average thickness of said inner side wall in a region bounded by two planes disposed transversely of the tuyère, one spaced from the innermost end of said chamber a distance equal to approximately one-tenth of the overall length of said chamber, the other of said planes being spaced from the inner extremity of said chamber a distance equal to approximately one-third of the overall length of said chamber, said nose wall having a minimum thickness at least equal to said average thickness of said outer side wall in said region.

5. In a tuyère, in combination, a nose wall, a

- rear wall, an inner side wall and an outer side wall forming an annular chamber for cooling medium, barriers extending from said nose wall within said chamber toward said rear wall, and means for causing cooling water to flow back and forth along said barriers longitudinally of said tuyère while traveling circumferentially of said tuyère, said outer side wall having an average thickness at least one and one-half times as great as the average thickness of said inner side wall in a region bounded by two planes disposed transversely of the tuyère, one spaced from the innermost end of said chamber a distance equal to approximately one-tenth of the overall length of said chamber, the other of said planes being spaced from the inner extremity of said chamber a distance equal to approximately one-third of the overall length of said chamber, the total thickness of said walls in the region between said planes tapering in thickness from said first-mentioned plane toward said second-mentioned plane, said nose wall having a minimum thickness at least equal to said average thickness of said outer side wall in said region.
6. In a tuyère, in combination, a nose wall, a rear wall, an inner sidewall and an outer sidewall forming an annular chamber for cooling medium, and means within said tuyère for setting up a high velocity of cooling water in the nose portion of said tuyère, the thickness of said outer side wall being at least one and one-half times the thickness of said inner side wall measured in a plane normal to the axis of said tuyère in a region bounded by two planes parallel to each other and

to said first-mentioned plane, one of said two planes being spaced from the innermost end of said chamber a distance equal to approximately one-tenth of the overall length of said chamber, the other of said two planes being spaced from the inner extremity of said chamber a distance equal to approximately one-third of the overall length of said chamber, said nose wall having a minimum thickness at least equal to said average thickness of said outer side wall in said region. 10

7. In a tuyère, in combination, a nose wall, a rearwall, an inner sidewall and an outer sidewall forming an annular chamber for cooling medium, barriers extending from said nose wall within said chamber toward said rear wall, and means for causing cooling water to flow back and forth along said barriers longitudinally of said tuyère while traveling circumferentially of said tuyère, the thickness of said outer side wall being at least one and one-half times the thickness of said inner side wall measured in a plane normal to the axis of said tuyère in a region bounded by two planes parallel to each other and to said first-mentioned plane, one of said two planes being spaced from the innermost end of said chamber 15 a distance equal to approximately one-tenth of the overall length of said chamber, the other of said two planes being spaced from the inner extremity of said chamber a distance equal to approximately one-third of the overall length of said chamber, said nose wall having a minimum thickness at least equal to said average thickness of said outer side wall in said region. 20

GORDON FOX.
